UNITED STATES PATENT OFFICE

123,342

DESIGN FOR A HANDBAG

Irving Pichel, New York, N. Y.

Application September 21, 1940, Serial No. 95,272

Term of patent 3½ years

To all whom it may concern:

Be it known that I, Irving Pichel, a citizen of the United States of America, residing in the city of New York, county of New York, and State of New York, have invented a new, original, and ornamental Design for a Handbag, of which the following is a specification, reference being had to the accompanying drawing, forming part thereof.

Fig. 1 is a front perspective view of a handbag showing my new design.

Fig. 2 is a rear perspective view illustrating the bottom portion of the bag.

I claim:

The ornamental design for a handbag, as shown.

IRVING PICHEL.
